UNITED STATES PATENT OFFICE.

EDMUND OCUMPAUGH, OF ROCHESTER, NEW YORK, ASSIGNOR TO DEFIANCE MACHINE COMPANY, OF ROCHESTER, NEW YORK, A CORPORATION OF NEW YORK.

CHECK-PRINTING MACHINE.

1,160,643.

Specification of Letters Patent.

Patented Nov. 16, 1915.

Application filed June 3, 1914. Serial No. 842,607.

To all whom it may concern:

Be it known that I, EDMUND OCUMPAUGH, a citizen of the United States of America, residing at Rochester, county of Monroe, 5 State of New York, have invented a new and useful Improvement in Check-Printing Machines, of which the following is a full, clear, concise, and exact description.

My invention relates particularly to the 10 construction of the table and platen supporting bridge and the guiding and holding devices which permit checks printed in blocks or sheets to be used instead of checks printed singly as heretofore.

15 The object of this invention is to provide a check printing machine through which checks may be fed in the form of sheets comprising a number of checks printed side by side and adapted to be separated after 20 filling in the blanks.

In carrying out this invention, I span the 25 entire table of the machine with a rigid platen supporting bridge which is removably secured to the table at its extremities, and under which sufficient space is left for the 30 checks to be readily inserted by the aid of guides hereafter described.

In order that the sheet of checks will pass 35 over the table freely under the pressure of the hand and still be held firmly against unintentional movement, and in order that the sheet may be readily started through the slot under the bridge, I provide guiding and clamping means at each edge of the 40 sheet. All of which is more fully described hereinafter and particularly pointed out in the claims.

My invention is illustrated in the accompanying drawings in which,

40 Figure 1 is a plan view of the mechanism; Fig. 2 is a perspective view of the bridge piece separated from the other parts of the machine; Fig. 3 is a cross-sectional view taken on the line 3—3 of Fig. 1; Fig. 45 4 is a fragmentary perspective view of the check guiding gaging and holding mechanism with sheet of checks inserted.

Similar letters of reference refer to similar parts wherever shown throughout the 50 several views.

This particular embodiment of my invention is shown associated with a printing machine having the type characters on a rotatable drum or cylinder 5, and having a 55 platen 6, adapted to press the check against

the type. I provide for that purpose a carrier table 7, having channeled guide-ways 8 and 9 extending from the front to the rear of the machine at each side of the table. Over this table from front to rear is passed 60 a sheet made up of several checks, turned printed side down, and in order to have the sheet lie flat, I provide the side springs 10, 11, adjustably supported at one end on the bridge piece 12 and connected at the other 65 end by means of the wire or rod 13. The forward ends of the springs are slightly bent up to facilitate the insertion of the sheet between them and the table, and the rod or wire 13 connects these ends so that 70 both springs may be raised at once by inserting a thumb or finger under either spring or the wire itself. The wire 13 also acts as a gage or spacing marker which may be adjustable to any position and set to determine the exact position for the various 75 checks for printing.

The sheet of checks will lie face, that is printed side, downward on the table, but the tear line between checks, whether perforated or merely printed, will always show from the reverse side. The wire 13 is preferably 80 so positioned that it will lie immediately over one of these lines when a check is in proper printing position.

The channel shaped side guides 8 and 9 have flanged entrances and are each provided with a very flexible leaf spring 17 for providing a slight resistance to the movement 85 of the sheet even when the springs 10 and 11 are raised.

The bridge piece 12 consists of the body portion 18, the ends of which are supported by screws 19 on the side frame-pieces 20, and of the center overhanging portion 21 95 for the support of the platen plunger 22 and handle 23. The handle 23 is pivoted at 24 and adapted to engage the plunger 22 at a point as near the pivotal point of the handle 100 as convenient in order to secure the best mechanical advantage.

An adjusting screw 25 is provided to adjust the handle, with respect to the plunger and the back stop portion 26 of the bridge piece, so that there will be no lost motion 105 between these parts. The plunger 22 is provided with a spring 27 to normally hold the handle and platen seat 6 in non-operative position. The platen seat 6 consists of a rigid bar having a longitudinal slot therein 110

in which is secured the soft rubber pad or platen 30.

By the foregoing arrangement I secure a substantial though light structure and one in which almost the entire table may be covered by the sheet of checks.

Many modifications could be made without departing from the spirit of my invention, and this particular embodiment should 10 therefore be taken merely as illustrative of the invention which is limited only by the scope of the appended claims.

I claim:

1. In a check writing machine, the combination with a table, an adjustable type carrier under the table, a bridge lying close to the face of the table and extending from one side to the other thereof, a platen and operating handle therefor carried by said bridge, a pair of adjustable leaf springs secured to and passing under the bridge, and a wire extending parallel to the platen and between the free ends of said springs for holding a sheet of checks in place and to gage the 25 positions of the sheet for printing.

2. In a check writing machine, adjustable printing mechanism, a containing case therefor having a flat top with a transverse slot therein through which a check may be 30 pressed to engage said adjustable printing mechanism, said top being free from obstructions either in front of or back of said slot, whereby checks may be passed over said slot in sheets, a stationary bridge attached 35 to said case at points on each side thereof and a platen carried thereby for pressing the check against said adjustable printing mechanism.

3. In a check printing machine for sheets 40 of checks having tear lines between the checks visible from the reverse side thereof, the combination with a table, of an adjustable gage coöperating with the tear lines between checks to indicate the proper printing 45 positions of the checks.

4. In a check printing machine, the combi-

nation with a table, of a bridge over the table, a leaf spring adjustably secured to and passing under said bridge and normally pressing against the surface of the table, a 50 gage carried near the free end of said spring said end being turned away from the surface of the table so that the spring may be readily lifted by the thumb or finger in sliding a check into printing position on the 55 table, said gage indicating the printing position for the check and said leaf spring holding the check in printing position when the finger or thumb is removed.

5. In a check printing machine, the combination with a table, of a bridge over the table, a pair of lineally adjustable leaf springs secured to said bridge, one at each side of the table, a member extending between said springs near the free ends thereof, whereby one spring may be lifted by lifting the other. 60

6. In a check printing machine, the combination with a table, of a bridge over the table, a pair of lineally adjustable leaf 70 springs secured to said bridge, one at each side of the table, a member extending between said springs near the free ends thereof, whereby one spring may be lifted by lifting the other, the free end of one of said 75 springs being bent away from the table so that may be readily raised by the finger.

7. In a check printing machine in which blocks of checks having tear lines between the checks visible from the reverse side 80 thereof are adapted to be fed for printing the value of the checks one at a time, the combination with a table, of an adjustable gage coöperating with the tear lines to indicate the proper printing positions of checks 85 of different widths.

In witness whereof, I hereunto subscribe my name this 9th day of May A. D., 1914.

EDMUND OCUMPAUGH.
